ATTORNEY.

UNITED STATES PATENT OFFICE

2,239,396

SLUICE

Roy M. Mowry, Huntington Park, Calif.

Application December 14, 1938, Serial No. 245,565

4 Claims. (Cl. 209—197)

My invention relates to sluices. An important object of my invention is to imitate as closely as possible nature's method of depositing gold by streams in gulches, and the like. Nature's method is for water rushing down a gulch to strike boulders therein, which splits the stream, causing eddies behind the boulders. The turbulence of the water rushing down the gulley, or the like, continuously turns upside down the stream and its suspended particles of gold, which prevents the flour and flake gold from floating off.

Another object is to provide mechanical means for imitating the roll of a placer pan manipulated by a miner.

Still another object is to provide novel agitating means within the sluice and novel means for catching the gold.

The invention also comprises novel details of construction and novel combinations and arrangements of parts, which will more fully appear in the course of the following description.

In the drawing, like reference characters designate similar parts in the several views.

Figure 1 is a side elevation of an embodiment of my invention.

Figure 2 is an enlarged cross section, taken on the line 2—2 of Figure 1.

Figure 3 is a face view of a track comprised in the invention.

Figure 4 is a broken, enlarged section of a water nozzle hereinafter more fully advised.

Referring more in detail to the drawing, the reference numeral 5 generally designates an inclined trough, at the head or feed end of which is a hopper 6 for delivering material to the trough. The trough is mounted on spring legs 7 and 8 respectively under the higher feed end and under the relatively lower discharge end of the trough. The legs may be braced as suggested at 9. The ends of the legs are preferably rigidly mounted on the trough and on base members 10. This mounting may be either through the intermediary of flanges at the ends of the legs, as shown at 12, or bolting the ends of the legs to angle irons, as shown at 13, or both means. The material of the legs is resilient, which affords a quick return of the trough, during agitation, without a jerk.

The bottom of the trough is preferably dished in cross section, as shown at 14 in Figure 2. This shape affords a relatively narrow, flat bottom 15. A series of riffles 16 is disposed longitudinally of the trough. The riffles span the space between the dished sides of the trough bottom, as shown in Figure 2, and are inclined upwardly from the

bottom 15 of the trough, as indicated in broken lines in Figure 1. Each riffle traps a small body of water behind it.

The recesses 17 under the riffles provide partial vacuums when water spills over the riffles, which provides suction, whereby to assist in deterring gold values from floating off.

Disposed longitudinally in the flat bottom 15 of the trough, between each adjacent pair of riffles, is a U-shaped, removable wire track or race 18 comprising rails 19 and a cross-head 20. The cross-heads are bowed upwardly to form stops 21, whereby to prevent balls 22 from striking the riffles 16. Each wire track is wedged between pairs of riffles, which prevents endwise movement of the tracks, which holds the tracks in position.

For the purpose of supplying water to mix with the feed material and to provide a current of water down the trough, a centrifugal pump 23 is mounted beneath the trough. A supply pipe 24 connects the pump with a water source. A conduit 25 connects the discharge orifice of the pump 23 with a nozzle 26 that empties into the hopper in the direction of the head end of the trough. A wire 27 is preferably mounted vertically in the nozzle to cut the stream therefrom.

It is believed clear without further illustration that the conduit 25 may be mounted directly to the trough, and connected with the pump by flexible tubing.

For the purpose of agitating the trough, an engine 28 is operatively connected to drive an eccentric 29 by means of a belt 30 on a sheave 31. A connecting rod 32 has a head 33 that follows the movements of the eccentric 29, and the other end of the rod 32 is connected with a bracket 34 under the bottom of the trough.

In the operation of the present invention, Figure 1 shows the extreme left position of the trough. In this position, it will be noted that the legs are inclined outwardly at approximately the same angle from the vertical. When the trough begins its return movement in the direction of the arrow A of Figure 1, the legs 7 will straighten up, which will raise the upper end of the trough slightly. At the same time the legs 8 will be further inclined from the vertical, which will cause the lower end of the trough to descend slightly. It will thus be noted that by my arrangement of the legs, a rocking, or cradle motion is obtained for the trough. This motion simulates the motion of a placer pan in the hands of a miner, and prevents the gold from creeping. Of course the normal positions of the legs 7 and

8 is somewhat to the right of the positions shown in Figure 1. Due to the substantially rigid mountings of the ends of the legs and to the resilience of the material of the legs, the return movements of the trough to the left and to the right are damped, which prevents jerky movements of the trough. 5

The agitation of the trough causes the balls to roll up and down on the tracks 18, which agitates the pools behind the riffles, so that the water will 10 be continuously roiled, thus deterring the flour and flake gold from floating off. The balls also simulate the boulders in nature's streams by dividing the stream that flows down the trough to its open discharge end 36.

The values collect in the pockets between the rails 19 of the tracks and underneath the balls. To remove the values, each ball and its respective track are removed. The fine material in the pocket may then be swept into a pan placed under 20 the lip of the riffle. A whisk broom may be used for the purpose. It will be noted that the operation of this mechanism is so simple that it may be operated by a person with little experience in placer separation. 25

It is also to be understood that the present mechanism may be used as an amalgamator by placing mercury in the spaces between the rails 19 of the wire tracks, although generally it is preferable to follow the steps outlined hereinbefore and then place the values in a separate amalgamator. Moreover, this machine may be used as a wet machine, as described, or if the water is omitted, it may be used as a dry concentrator. 35

The wires 18 are of value in taking up the wear caused by the agitation of the balls. When worn, the wires may be easily replaced, which would not be the case if the balls rested directly on the bottom of the trough. 40

While I have illustrated and described what I now regard as the preferred embodiment of my invention, the construction is, of course, subject to modifications without departing from the spirit of my invention. I, therefore, do not wish to restrict myself to the particular form of construction illustrated and described, but desire to avail myself of all modifications which may fall within the scope of the appended claims. 45

Having thus described my invention, what I claim and desire to secure by Letters Patent is: 50

1. A sluice comprising an inclined trough, riffles successively arranged down the trough, the riffles being arranged at an acute angle to the trough bottom, to provide recesses thereunder, tracks arranged in the trough bottom between the riffles and extending in the direction of the inclination of the trough, balls loosely supported on the trough tracks, and means to vibrate the trough longitudinally with respect to the inclination of the trough.

2. A sluice comprising an inclined trough, a riffle in the trough arranged to impound a relatively small pool, a track disposed in the pool, the track having substantially parallel members providing a pocket therebetween for catching values, the parallel members of the track extending lengthwise of the inclination of the trough, a ball disposed to roll along the track when the trough and its said concomitant members are agitated, and means to vibrate the trough a direction lengthwise of said track members.

3. A sluice comprising a trough, riffles in the trough, inclined wire tracks in the trough wedged in between adjacent riffles, the track having a bowed, cross member at the lower end of the track, balls movably disposed on the tracks, the cross members acting as stops for the balls, and means to vibrate the trough.

4. In a sluice, a trough, arm means rigidly connected with and supporting the head of the trough, relatively shorter arm means rigidly connected with and supporting the foot of the trough, at least one of said arm means being resilient, the arm means being different distances apart at their outer ends than at their points of connection with the trough, a support rigidly connected with the outer ends of the arm means, the arm means being inclined outwardly in opposite directions from the vertical in one position of the trough, movement of the trough from said position against the resilience of the arm means causing the arm means to move the ends of the trough in opposite directions in vertical planes, and mechanism to effect said movements, the resilience of the arm means tending to effect a snap movement on the return movement of the trough.

ROY M. MOWRY.
